UNITED STATES PATENT OFFICE.

SYLVESTER NELSON, OF DETROIT, MICHIGAN.

METHOD OF MANUFACTURING AXLES.

1,129,418.

Specification of Letters Patent. Patented Feb. 23, 1915.

Original application filed July 16, 1914, Serial No. 851,254. Divided and this application filed September 8, 1914. Serial No. 860,506.

To all whom it may concern:

Be it known that I, SYLVESTER NELSON, a citizen of the United States of America, residing at Detroit, in the county of Wayne and State of Michigan, have invented certain new and useful Improvements in Methods of Manufacturing Axles, of which the following is a specification, reference being had therein to the accompanying drawings.

This is a division of my application filed July 16, 1914, Serial No. 851,254, for improvements in axle dies, and the present invention relates to a method of manufacturing axles, irrespective of any particular type of dies or apparatus.

The object of this invention is to provide a method by which automobile axles can be expeditiously and economically produced ready for installation in connection with other parts of a vehicle. The method involves, first, the upsetting or shaping of the ends of the blank to provide spring perches and heads; second, stamping or cutting the ends of the blank to form hooks; third, opening the hooks, and fourth, bending and shaping the hooks to provide forks. These steps or operations are successively performed with a degree of accuracy that insures a minimum amount of waste, and to carry such steps or operations into effect independent instrumentalities, suitable apparatus, or dies may be employed.

As illustrating one manner of carrying my invention into effect, I will describe, with the assistance of the accompanying drawing, dies and a *modus operandi* as now practised by me.

In the drawing, Figure 1 is a perspective view of an axle blank; Fig. 2 is a plan and elevation of an end of a blank having received the first operation involving my method; Fig. 3 is an elevation and section of a portion of the blank illustrating the second operation on the blank; Fig. 4 is a side elevation of a portion of the blank illustrating the third operation; Fig. 5 illustrates the fourth operation on the blank, showing the dies in plan; Fig. 6 is a side elevation of one of the dies illustrating the fifth operation on a blank; and Fig. 7 is a perspective view of separated dies that can be advantageously used for carrying my method into effect.

In the drawings, the reference numeral 12 designates a blank in the form of a bar

that is rectangular in cross section. The first operation upon the ends of this bar is that of providing the same with spring perches 16 and heads 15. This operation is accomplished by holding the bar and upsetting the ends thereof, the metal of the bar bulging or extending at such points as are permissible by the holding means of the blank. For holding the blank during this first operation, dies designated A and B of Fig. 7 can be employed, said dies having the confronting faces thereof provided with grooves 1 and grooved yieldable formers 4 to receive the end of the blank. With the axle blank frictionally held between the dies, an upsetting tool or header 13 is brought into engagement with the end of the blank. This tool has a recess 14 to receive the end of the blank and as said tool is brought into action, the protruding end of the blank is upset and shaped in the enlarged ends of the grooves of the yieldable formers. Beside the outer ends of the blank being shaped by said formers and the recess in the header 13, the blank is upset at the ends of the grooves 1 of the dies and the ends of the grooves 8 in the yieldable formers. The spring perches 16 are thus simultaneously formed with the heads 15 and the blank is now ready to receive the second operation.

The second and successive operations are simply in connection with the head 15 and said head is pressed between the dies and caused to enter stamping recesses 17. These recesses are shaped to form a hook shaped head having a shank 18, a bill 19 a tang 20 and a connecting web 21. After this second operation the head is shifted to a position between the dies where the web 21 can be punched or cut from the head. One of the dies has a punching member 25 in a recess 23 thereof, and the recess of the other die has an opening 24 for the removal of the cut web, without distorting the blank.

The next or fourth operation consists of opening the hook shaped end of the blank to form a fork and this can be accomplished upon the top of the dies by providing the die B with means for holding the blank and the die A with a hook opening member 28. This member is angularly disposed and adapted to engage the bill 19 of the blank hook, when the dies A and B are brought together. The hook is opened by bending the shank 18 against a block 26 coöperating

with the pin 27 in properly holding the blank upon the dies.

The blank is now ready for a finishing and shaping operation which is accomplished by placing the blank in grooves 29 properly shaped and provided therefor in the confronting faces of the dies A and B. The blank held between the dies and the open hook in recesses 31, a finishing or 10 shaping tool 32 enters the recesses and properly shapes the fork. This is best illustrated in Fig. 6 and it will be observed that the operation which takes place is simply that of bending the shank and bill of the 15 hook whereby the bill will aline with the tang and thus form a fork in which the knuckle of a wheel or steering apparatus can be pivotally mounted.

From the above it will be observed that 20 the dies can be advantageously used in connection with the tools for performing the various steps or operations of my improved method, yet, separate dies, independent devices, or other means can be employed, consequently, I do not care to confine my invention to any specific device or instrumentality 25 for carrying the same into effect, than defined by the appended claims.

What I claim is:—
30 1. A method of manufacturing axles con-

sisting of upsetting the end of an axle blank to form a head, stamping the head to form a hook, and then opening the hook to form the fork.

2. A method of manufacturing axles 35 consisting of upsetting the end of an axle blank to form a perch and a head, stamping and punching the blank head to form a hook, and then opening the hook to form a fork 40 at the end of the blank.

3. A method of manufacturing axles from 45 blanks, consisting of holding the blank between dies and upsetting the end thereof to form a head, stamping and punching the blank head to the shape of a hook, opening the bill of the hook to form a fork, and then shaping the fork while the blank is held by the dies.

4. A method of manufacturing axles from 50 blanks consisting in providing a blank with a hook shaped head, opening the hook shaped head and then shaping the head while the blank is held between dies to form a fork.

In testimony whereof I affix my signature 55 in presence of two witnesses.

SYLVESTER NELSON.
